(57) CLAIM

The ornamental design for a head mounted augmented reality device, as shown and described.

DESCRIPTION

FIG. 1 is a top perspective view of a head mounted augmented reality device, showing our new design;

FIG. 2 is a bottom perspective view thereof;

FIG. 3 is a top view thereof;

FIG. 4 is a bottom view thereof;

FIG. 5 is a left view thereof;

FIG. 6 is a right view thereof; and,

FIG. 7 is a front view thereof.
